UNITED STATES PATENT OFFICE.

ARTHUR W. KNIGHT, OF LOS ANGELES, CALIFORNIA, ASSIGNOR TO THE CELITE COMPANY, OF LOS ANGELES, CALIFORNIA, A CORPORATION OF DELAWARE.

DESIGN FOR A FRONT PAGE FOR SERIAL PUBLICATIONS.

Application filed December 23, 1925. Serial No. 15,838. Term of patent 14 years.

To all whom it may concern:

Be it known that I, ARTHUR W. KNIGHT, a citizen of the United States, residing at Los Angeles, in the county of Los Angeles and State of California, have invented a new, original, and ornamental Design for a Front Page for Serial Publications, as shown in the accompanying drawing, forming part of this specification.

The drawing shows the design for a front page for serial publications.

The design comprises a border of a distinctive color, surrounding a plain field, the border being divided into series of squares or sections by parallel lines of a contrasting color crossing each other at right angles.

I claim:

The ornamental design for a front page for serial publications, substantially as shown and described.

ARTHUR W. KNIGHT.
